Primary Examiner — Calvin E Vansant*Assistant Examiner* — Jonathan E Fiencke(74) *Attorney, Agent, or Firm* — JCIPRNET(57) **CLAIM**

The ornamental design for a temperature control collar as shown and described.

DESCRIPTION

FIG. 1 is a first perspective view of a temperature control collar showing my new design;

FIG. 2 is a second perspective view thereof;

FIG. 3 is a front view thereof;

FIG. 4 is a left side view thereof;

FIG. 5 is a right side view thereof;

FIG. 6 is a top view thereof;

FIG. 7 is a bottom view thereof; and,

FIG. 8 is a cross-section view taken along line 8-8 in FIG. 3.

The broken lines depict portions of the temperature control collar that form no part of the claimed design.

1 Claim, 8 Drawing Sheets(56)
